UNITED STATES PATENT OFFICE

KRESTINE KNUDSEN, OF OAKLAND, CALIFORNIA

DESIGN FOR A DOLL

Application filed January 25, 1930. Serial No. 34,288. Term of patent 3½ years.

To all whom it may concern:

Be it known that I, KRESTINE KNUDSEN, a subject of the King of Denmark, residing at 403 Forty-third Street, in the city of Oakland, county of Alameda, and State of California, have invented a new, original, and ornamental Design for a Doll, of which the following is a specification, reference being had to the accompanying drawing, forming part thereof.

Fig. 2 is a side elevation of a doll, showing my new design.

I claim:

The ornamental design for a doll, substantially as shown.

KRESTINE KNUDSEN.
